UNITED STATES PATENT OFFICE.

JOHN ALBERT WESTBROOK, OF BRADY, TEXAS, ASSIGNOR OF ONE-HALF TO JOE A. ADKINS, OF BRADY, TEXAS.

PACKER FOR SILOS.

1,104,333.

Specification of Letters Patent.

Patented July 21, 1914.

Application filed October 7, 1913. Serial No. 793,974.

To all whom it may concern:

Be it known that I, JOHN A. WESTBROOK, a citizen of the United States, residing at Brady, in the county of McCulloch and State of Texas, have invented a new and useful Packer for Silos, of which the following is a specification.

The device forming the subject matter of this application is adapted to be employed 10 upon silos for packing the ensilage therein.

One object of the present invention is to provide a device of the type above indicated which may be readily assembled with any silo of standard construction, to carry out 15 the packing operation.

Another object of the invention is to provide novel means for maintaining in proper relation with respect to each other, the several elements in which the packer shaft is 20 received.

Another object of the invention is to provide novel means whereby the packer shaft may be lengthened or shortened at will.

It is within the scope of the invention to 25 improve generally and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

In the accompanying drawing:—Figure 1 shows the invention in elevation, mounted 40 upon a silo, the silo being partly broken away; Fig. 2 is a fragmental top plan of the frame in which the rotatable and slidably elements of the structure are mounted; Fig. 3 is a perspective showing the packing element; Fig. 4 is a fragmental elevation showing the means whereby the adjacent ends of the shafts are connected, parts being 45 broken away; Fig. 5 is a perspective showing one blade of the packing element together with the head whereby the said blade is carried; Fig. 6 is a perspective showing a slight modification in the invention.

In the accompanying drawings there is 50 shown a silo 1 which may be of desired form. Mounted upon the upper end of the

silo 1 is a frame 2, the same being shown as comprising a base 3 and a cap 4, there being spacers 5, 6 and 7 interposed between the base and the cap. Strap bolts 8 extend upwardly through the base 3 and carry 60 washers 9 engaged by nuts 10 which coöperate with the upper face of the base 3. The lower ends of the strap bolts 8 are connected with the side wall of the silo 1 by means of attaching elements 11 of any desired 65 sort. Obviously, any suitable means may be provided for connecting the frame 2 with the silo 1.

A horizontally disposed shaft 12 is journaled for rotation in the spacers 7 and 6 70 and is provided at its outer end with a pulley 14 or any other suitable means whereby rotary movement may be imparted to the shaft 12 from a prime mover. Secured to the inner end of the shaft 12 is a 75 pinion 15, meshing into a horizontally disposed gear wheel 16, positioned between the base 3 and the cap 4. Balls or other anti-frictional elements indicated at 17 are interposed between the lower face of the gear 80 wheel 16 and the base portion 3 of the frame 2. An annular spacer 18 is mounted between the wheel 16 and the cap 4.

Extended through the base 3, the cap 4, the wheel 16 and the spacer 18 is a shaft 19 85 provided with a longitudinally extended keyway 20 adapted to be engaged by a key 21 carried by the gear wheel 16. From the foregoing it will be seen that when the wheel 16 is rotated, the shaft 19 will be rotated also, the shaft, however, being permitted to slide longitudinally, owing to the key and keyway construction 21—20.

At this point it may be noted that the removable spacer exercises two functions. 95 First, it permits the anti-friction elements 17 to be interposed between the gear wheel 16 and the base 3 and to hold the gear wheel 16 in place; and secondly, the spacer 18, being engaged with the upper end of the 100 key 21 serves to prevent an accidental displacement of the key.

The shaft 19 preferably comprises a plurality of sections 22 each section being equipped at one end with a reduced, 105 threaded tip 24 and being provided at its opposite end with an internally threaded socket 25, the construction being such that one section of the shaft may be threaded readily into another section thereof to per- 110

mit an elongation or a shortening of the shaft. Surrounding the shaft 19 is a collar 26, held in place by a set screw 27. This collar 26 is adapted to engage the cap 4 5 and serves to uphold any one section of the shaft while another section of the shaft is being threaded thereinto. This feature is of great importance when the structure is being set up for use. Further, referring to Fig. 1, 10 it will be observed that the collar 26 may be slid upwardly toward the extremity of any section of the shaft which is about to be removed, and when the set screw 27 is engaged in the keyway 20, the collar constitutes a means whereby the section which is about to be removed may be rotated to disengage the tip 24 from the socket 25.

Secured to the lower end of the shaft 19 is a head 28, in the present instance shown 20 as of rectangular form. In the side faces of the head 28 are formed diagonally disposed openings 29, adapted to receive the reduced tongues 30 formed at the inner ends of blades 31, the blades 31 and the head 28 25 constituting a packing element. The blades 31 are disposed at an angle to the axis of the shaft 19, as will be understood from Fig. 3. The construction is such that when the shaft 19 is rotated in one direction, the 30 blades will serve to compact the ensilage into the silo. When, however, the shaft 19 is rotated in an opposite direction, the blades may be employed for loosening up the ensilage.

35 The practical operation of the structure hereinbefore described is as follows: Rotary movement is imparted to the shaft 12 by means of the pulley 14, the pinion 15 meshing into the gear wheel 16 and imparting 40 a rotary movement to the shaft 19 and the blades 31, through the medium of the key 21 and the keyway 20. As the ensilage ac-

cumulates in the silo, the shaft 19 and the parts carried thereby will move upwardly 45 and as an increment of material is deposited in the silo 1, the material will be packed down firmly, by the rotating blades 31.

It is of course to be understood that the packer may be so constructed as to fit silos of any size. Further, if desired, the blades 31 may be replaced by rollers 31^a as shown in Fig. 6.

Having thus described the invention, what is claimed is:

1. In a silo packer, a frame comprising a base and a cap; a wheel disposed between the base and the cap; anti-friction elements located between the wheel and the base; a spacer interposed between the wheel and the cap and removable to permit the wheel and the anti-friction elements to be placed between the base and cap; a shaft mounted to slide in the wheel; a packing element carried by the shaft; and means for connecting the wheel and the shaft for simultaneous 60 rotation.

2. In a silo packer, a frame comprising a base and a cap; a wheel located between the base and the cap; a shaft mounted to slide 70 in the wheel and provided with a key way; a key in the wheel and engaged in the keyway; a spacer surrounding the shaft and interposed between the wheel and the cap, the spacer constituting means for retaining the key in place and constituting also a 75 slide-bearing for the shaft; and a packing element carried by the shaft.

In testimony that I claim the foregoing as my own, I have hereto affixed my signature in the presence of two witnesses.

JOHN ALBERT WESTBROOK.
